UNITED STATES PATENT OFFICE.

FREDERICK COLLEY, OF JOHNSTOWN, PENNSYLVANIA, ASSIGNOR TO THE JOHNSON STEEL STREET RAIL COMPANY, OF KENTUCKY.

ROLLS FOR ROLLING OVERHANGING SLOT-RAILS.

SPECIFICATION forming part of Letters Patent No. 387,147, dated July 31, 1888.

Application filed June 12, 1888. Serial No. 276,824. (No model.)

To all whom it may concern:

Be it known that I, FREDERICK COLLEY, of Johnstown, in the county of Cambria and State of Pennsylvania, have invented new 5 and useful Rolls for Rolling Overhanging Slot-Rails, which invention is fully set forth and illustrated in the following specification and accompanying drawings.

The object of this invention is to provide a 10 set of rolls for rolling slot-rails for cable rail-ways of the form hereinafter described.

The invention will first be described in detail, and then particularly set forth in the claim.

15 The accompanying drawings, consisting of two figures, marked, respectively, Figure 1 and Fig. 2, illustrate two pairs of rolls, the upper roll of each pair being indicated by the letter U, and the lower roll by the letter L. 20 Said rolls contain, collectively, eleven passes, distributed in each pair as follows: Five passes, as shown in Fig. 1, numbered 1 to 5, inclusive; and six passes, as shown in Fig. 2, numbered 6 to 11, inclusive.

25 The manipulation of the hot metal and the operations of the rolls upon it are performed in the following manner: Pass No. 1 is an ordinary "slabbing" pass, after being rolled through which the billet is entered diagonally 30 and run through pass No. 2. The metal is then entered, after leaving pass No. 2, into and rolled through pass No. 3, excess of work or draft having been brought upon the metal in the former pass at the point A. Turned once,

35 the metal is then entered in and rolled through pass No. 4, in which it is subjected to excess of draft at the point B. Entered next in pass No. 5, without turning, excess of draft is thrown on the metal at the point C, and an 40 angle is thereby thrown at said point into the head portion of the rail in process of formation. In passes Nos. 6, 7, and 8 such angular

formation of head portion is still maintained and increased, excessive draft being concentrated on the shoulder portion of the metal 45 (marked D) in said passes. In passes Nos. 9, 10, and 11 the operation consists principally in the truing up and finishing of the rail to the exact form of cross-section desired, the main portion of the draft being concentrated 50 upon the flange portion of the rail (marked E) in said passes. It will be observed that throughout the design of these rolls each pass concentrates an excess of draft upon a specific portion of the mass of metal being rolled, instead of distributing the draft over the whole 55 of such mass generally—that is to say, such treatment is locally concentrated and the rest of the draft distributed with a view to this local concentration. 60

In the drawings, Fig. 1 shows roughing-rolls and Fig. 2 finishing-rolls; but I do not limit myself to the exact number or distribution of passes shown, as the number of passes and their distribution into roughing and finish- 65 ing passes is to a certain extent arbitrary, being influenced by the length and diameter of the rolls, a light train of rolls calling for more passes with lighter draft than a heavy roll-train. It is also evident that the rolls can, if 70 desired, be made three-high instead of two-high, as shown.

Having thus fully described the construction and operation of my said rolls, as of my invention I claim—

75 A set of rolls for rolling overhanging slot-rails, having passes of the conformations indicated in the accompanying drawings by the numbers 1 to 11, inclusive, substantially as set forth.

FRED. COLLEY.
